POLK BOALS, OF NEW YORK, N. Y.; RICHARD LEANDER HALL, ADMINISTRATOR OF SAID BOALS, DECEASED, ASSIGNOR OF ONE-HALF TO ARGY G. CAMERON, OF NEW YORK, N. Y.

VENDING MACHINE.

Application filed December 18, 1925. Serial No. 76,238.

This invention relates to vending machines.

The principal object of the present invention is to provide a machine for vending goods or merchandise, which is characterized by means which will indicate to an attendant that a patron contemplates making a purchase, and to indicate that the patron has deposited a coin; the machine being of a self-service type and to be known as a "cacheteria."

Another object of the present invention is to provide a machine for vending goods or merchandise expeditiously and conveniently; a patron being able to make a purchase without the assistance of an attendant.

Another object of the present invention is to provide a self-service vending machine which will be comparatively simple of construction, which will be reliable in operation, and which will be comparatively inexpensive.

The nature of the invention and its distinguishing features and advantages will appear when the following specification is read in conjunction with the accompanying drawing, in which:

Figure 1 is a perspective view of the machine of the present invention.

Fig. 2 is a sectional view taken substantially on the line 2-2 of Fig. 1, and showing the condition of the working parts when the cover of the casing of the machine is in a closed position.

Fig. 3 is a view illustrating the working parts just prior to the release of the striker or clapper which sounds one of the bells to indicate that the cover of the casing of the machine is being opened.

Fig. 4 is a detail view on an enlarged scale illustrating some of the working parts of the machine.

Fig. 5 is a perspective view of the element which actuates the striker or clapper and the coin holding and releasing element.

Fig. 6 is a perspective view of the coin holding and releasing element.

The present invention in actual practice contemplates the use of a casing 10 which may be of any preferred design and construction, and in the present instance constitutes a walled enclosure having a cover 11 hingedly connected as at 12 to the front edge of the top wall 13. The cover in the present instance is supported in a closed po-

sition at an angle and has a transparent panel 14 through which the goods or merchandise may be viewed. The goods or merchandise is arranged in one end of the casing 10 which will be in the nature of a magazine for accommodating the goods or merchandise which may be held in individual packages or which may be held in quantities in a single receptacle or container, such as a box of cigars for instance, indicated at 15.

In the present instance the box of cigars is supported beneath the cover 11 on suitable supports 16 which are held in place in any suitable manner from the side walls of the casing 10. It is to be noted that the box of cigars is supported at an angle to correspond substantially to the angle of inclination of the cover 11. At the top and rear of the casing 10 there is provided a holder 17 which serves for holding a suitable placard or advertiser, which will advertise the goods within the machine. It is known that cigar boxes usually carry on the inside of the cover thereof a label, and such cover when removed from the box may be readily placed in the holder 17, as indicated in Figs. 1, 2, and 3 of the drawing, the cover being shown at 18.

In order that it may be indicated to an attendant that a patron who contemplates making a purchase has raised the cover 11 there is provided a means which operates in response to the movement of the door presently to be described. On the cover 11 is arranged an arm 19. The arm 19 at the free end thereof is provided with a cam 20. Arranged for oscillation on a stud 21 carried by one of the side walls of the casing 10 is an element 22.

The element 22 is provided with a member 23 whose edge 24 is disposed at an angle with respect to a vertical plane when the element 22 is in a normal position.

The said element 22 is also provided with members 25 and 26 respectively at opposite side edges thereof. A striker or clapper 27 is provided which is suspended from the stud 21 for oscillation, the said striker being arranged between a collar or nut 28 on the stud 21 and the element 22 so that the member 25 will be engageable with a portion of the striker 27 upon the movement of the element 22. The element 22 is moved in one direction by virtue of the coaction of the cam 20 on the arm 19 and the member 23 when the cover 11 is raised, as shown most

clearly in Fig. 3. After the cam 20 rides off the member 23, the element 22 and the striker 27, which latter has been raised with the element 22, under their own weight oscillate which results in the striker 27 striking a bell 29. The bell 29 may be supported in any suitable manner, and in the present instance is carried on a stud 30 carried by a bracket 31 attached to a side wall of the casing 10.

In order that a patron may deposit a coin and that an attendant may be assured that a coin has been deposited in the machine there is provided a means which consists of parts and operates in a manner presently to be described. Supported by the top wall 13 and extending into the interior of the casing 10 near the back thereof is a coin chute 32 which is arranged directly over a bell 33 carried by an arm 34 which in turn is carried by a bracket 31. An element 35 is employed, and the said element 35 is suspended for oscillation on the stud 21. The element 35 is provided with a weight 36 and a coin holding and releasing member 37. The element 35 is arranged adjacent the element 22 so that a portion thereof will be capable of engagement by the member 26 when the element 22 is moved clockwise. The clockwise movement of the element 22 is effected when the cover 11 is lowered, due to the fact that the cam 20 will ride on the angular edge 24. The element 35 will, therefore, be caused to move with the element 22 in a clockwise direction and as a result the member 37 will be moved from its normal coin holding position beneath the outlet end of the coin chute 32 to a position to one side of the outlet end of the coin chute so that a coin deposited in the coin chute will be allowed to drop on a bell 33 to cause the same to ring. It is to be understood that the bells 29 and 33 constitute sound producers, and each of the bells is of a distinctive tone. The idea is to have a sound producer, such as a bell, which will ring when the cover 11 is raised to indicate to an attendant that a patron is about to select some of the goods or merchandise in the machine and to have a second sound producer, such as a bell, which will ring and be of a different tone or quality distinguishable from the tone of the other bell to indicate to an attendant that a coin has been deposited in the machine.

From the foregoing it will be apparent that there has been described a machine which is of the self-service type and some of its advantages may be enumerated as follows: It saves time for the patron or customer; obviates the ringing up of sales; obviates the issuance of sales tickets and, therefore, reduces the cashier's work; permits attendants or clerks to serve more quickly other patrons or customers; and

segregates the receipts in connection with the particular product of merchandise thus permitting a merchant to positively know each day the extent of its demand.

It is to be understood that the invention is not restricted to the precise arrangement of parts shown and described as details of construction may be modified and substitutions may be made and the parts rearranged without departing from the spirit of the invention, the scope of which is limited only by the terms of the appended claims.

What I claim is:

1. In a vending machine, a receptacle having a cover capable of being raised and lowered for the removal of an article of merchandise in said receptacle, a coin depository, a signal rendered active by a cover operated means upon the raising of the cover, and a second signal rendered active by a coin which is released from said depository by a cover operated means upon the lowering of the cover.

2. In a vending machine, a receptacle having a cover capable of being raised and lowered for the removal of an article of merchandise in said receptacle, a coin depository, an audible signal rendered active by a cover operated means upon the raising of the cover, and a second audible signal rendered active by a coin which is released from said depository by a cover operated means upon the lowering of the cover.

3. In a vending machine, a receptacle having a cover capable of being raised and lowered for the removal of an article of merchandise in said receptacle, a coin depository, an audible signal rendered active by a cover operated means upon the raising of the cover, and a second audible signal of a tone distinguishable from the tone of the first mentioned signal, said second audible signal rendered active by a coin which is released from said depository by a cover operated means upon the lowering of the cover.

4. A vending machine comprising a merchandise receiving receptacle having a hingedly connected lid with a transparent panel, means in the receptacle for supporting the merchandise beneath the lid, a bell, means operable in response to the raising of the lid for ringing said bell, a coin chute, a second bell in line with said coin chute below the same, a coin holding and releasing member normally disposed at the lower end of the coin chute, and means operable in response to the lowering of the lid for moving said member to release a coin in said coin chute to permit the coin to drop on said second bell.

5. A vending machine comprising a merchandise receiving receptacle having a hingedly connected lid with a transparent panel, means in the receptacle for supporting the merchandise beneath the lid, a bell,

means operable in response to the raising of the lid for ringing said bell, a coin chute, a second bell in line with said coin chute below the same, a coin holding and releasing member normally disposed at the lower end of the coin chute, means operable in response to the lowering of the lid for moving said member to release a coin in said coin chute to permit the coin to drop on said second bell, and means for returning the said member to and for releasably maintaining the said member in a coin holding position beneath said coin chute.

6. In a vending machine, a receptacle having a cover capable of being raised and lowered for the removal of an article of merchandise in said receptacle, a coin chute extending into the interior of said receptacle, a bell in line with said coin chute below the same, a coin holding and releasing member having a normal disposition to hold a coin in said chute, said member being actuated by cover operated means to permit the coin to drop out of said coin chute, the coin dropping on said bell to cause the same to ring, and means for returning said member to its normal position.

7. A vending machine comprising a casing having a connected cover capable of being raised and lowered, a magazine in said casing for the reception of merchandise, a coin chute extending into the interior of said casing, bells of different tonal qualities, one of said bells being arranged below said coin chute in line therewith, a striker mounted for swinging movement, means operable in response to the raising of the cover for moving and releasing the striker so that the striker will swing under its own weight to strike and ring one of said bells to indicate that the cover has been raised, a coin holding and releasing member normally disposed at the lower end of said coin chute to prevent a coin placed in said chute from passing out of the same, means operable in response to the lowering of said cover to permit said coin to drop out of said coin chute which will drop on the other of said bells to ring the same to indicate that a coin has been deposited, and means for returning said member to and for releasably maintaining said member in a coin holding position.

POLK BOALS.
